X-RAY TUBE CATHODE

Zed J. Atlee, Chicago, Ill., assignor to Dunlee Corp.,
Chicago, Ill., a corporation of Illinois

Application March 28, 1955, Serial No. 497,151

1 Claim. (Cl. 313—57)

The present invention relates to X-ray tubes and more particularly to new and improved cathode structure for an X-ray tube.

Self-rectified X-ray tubes conventionally comprise a cathode and an anode mounted in facing, spaced relation within a sealed, evacuated glass envelope. The cathode is provided with a filament for generating a beam of electrons which is focused upon a wolfram target embedded in the anode, the filament being mounted in a metal body usually designated as the cathode head portion. The bombardment of the target by the electrons from the cathode filament causes X-rays to be emitted from the target, but the continual bombardment of the target with electrons also causes it to become heated as a consequence of which it emits electrons. The electrons emitted from the target are usually designated as inverse electrons and are emitted from the target surface in a direction normal to the plane of the target face. For various reasons, it is desirable to design an X-ray tube so that the inverse electron beam from the anode target strikes the surface of the cathode head portion below the filament or to one side thereof with structure as shown in my prior Patent 2,671,867, in turn causing heating of the material of the head portion at the point where the inverse electron beam strikes the same.

If excessively heated, the material of the head portion may melt and vaporize, the vaporized metal depositing or condensing upon the colder parts of the tube such as the envelope which is undesirable since such deposits impair the efficiency of the tube and may even render a tube inoperable. Inasmuch as the intensity of the inverse electron beam is directly proportional to the operating ratings of the tube, it has been necessary to operate a tube at ratings sufficiently low that the intensity of the inverse electron beam was below the point where it would cause excessive heating and vaporizing of the material of the cathode head portion. Heretofore, cathode head portions have been formed of nickel or iron or alloy thereof and which melted and vaporized under impingement by the inverse electron beam even though a tube was operated at a rating considerably below that at which it otherwise could have been operated. Attempts have been made to protect such head portions by mounting an insert of a high melting point material such as molybdenum or wolfram therein at the inverse focal spot or by providing a layer of such material on the surface of the head portion. But such procedures are expensive and even with the protective material, the possibility of injuring the cathode remained the limiting factor in the tube operation. It is, therefore, a principal object of the invention to provide a new and improved X-ray tube structure which reduces or negates the problem of inverse electron emission from the anode target as a limiting factor in the operable rating of the tube.

More particularly, it is an object of the invention to provide a new and improved cathode structure for self-rectified X-ray tubes which is not prone to injury upon

2

bombardment by the inverse electron emission from the anode.

Still another object is to provide an inexpensive cathode structure not subject to vaporization or melting under bombardment by the inverse electron beam from the anode.

Other objects and advantages of the invention will become more apparent hereinafter.

In accordance with the present invention, the X-ray tube cathode is constructed with a head portion of copper which it has been discovered will not be injured even though the tube is operated at a rating greatly exceeding that which would be permissible with a cathode constructed in accordance with the prior art. In fact, with a copper cathode head the limiting factor in the tube rating is the ability of the anode structure to withstand injury since the cathode head will not be injured even when the tube is operated at ratings which cause injury to the anode target.

For a more detailed description of the invention, reference is made to the accompanying drawings and the detailed description thereof wherein:

Fig. 1 is a longitudinal, sectional view taken through an X-ray tube constructed in accordance with the present invention;

Fig. 2 is an enlarged, longitudinal, sectional view through the anode and cathode of the X-ray tube;

Fig. 3 is a view looking in the direction of the arrows 3—3 of Fig. 2 and showing the face of the anode; and

Fig. 4 is a view looking in the direction of the arrows 4—4 of Fig. 2 and showing the face of the cathode.

The illustrated X-ray tube comprises an anode 10 and a cathode 11 mounted in coaxial, facing relationship within a sealed glass envelope 12.

The anode 10 comprises a copper body 14 secured in any suitable manner to the envelope 12 and formed with a target face which is inclined with respect to the longitudinal axis of the tube and in which face is embedded a planar faced target element 15 of wolfram or similar material capable of generating X-rays upon bombardment with electrons. The face of the anode and target element is normally inclined with respect to the axis of the tube, as shown, so that a substantially uniform beam of X-rays indicated at 16 will be emitted laterally through the walls 45 of the envelope 12.

The cathode 11 comprises a mounting sleeve 18, one end of which is fitted telescopically over the end of a re-entrant, cylindrical glass stem portion 19 of the envelope 12 and suitably secured thereto such as by 50 means of a plurality of turns of wire 20. Mounted in the end of the sleeve 18 facing the anode 10 is a massive head block or head portion 22 in which is formed an electron focusing cup 23 wherein is disposed an electron emitting filament 24. The filament 24 is adapted to be energized 55 through leads 25 extending outwardly through the stem 19 of the envelope. The head 22 may be secured to the sleeve 18 by any suitable means such as screws 26.

As is well known, heating of the filament 24 causes the same to emit electrons and the application of potential 60 between the cathode 11 and anode 10 causes the electrons to travel from the filament to the anode. The cathode cup 23 is shaped so as to focus the electrons upon the anode target in a concentrated electron beam indicated at 30, striking the target 15 in restricted area or focal spot 31.

The impingement of the electron beam 30 upon the target 15 will heat the target in the area of the focal spot 31 whereupon electrons will be emitted from the heated portion of the target. As has been indicated hereinbefore, such electrons tend to leave the target in a direction at 65 right angles to the plane of the target surface in an inverse electron beam such as indicated at 32 in Fig. 2.

It will be understood that in the operation of a self-

rectified tube an alternating current potential is applied between the anode 10 and cathode 11. During the half cycle that the cathode 11 is negative with respect to the anode 10, electrons will flow from the cathode to the anode by way of the beam 30. During the other half cycle, when the anode becomes negative with respect to the cathode, the inverse electrons will flow from the target 15 towards the cathode.

The intensity of the X-rays generated at the target of an X-ray tube is proportional to the intensity of the loading of the focal spot 31 of target 15, the loading ordinarily being expressed in terms of watts/sq. cm. of focal spot. The loading or tube rating may be increased by increasing the potential applied between the cathode and anode, by increasing the electron generation at the filament, or by concentrating the electrons in a smaller focal spot on the anode target. As the loading or rating on the target 15 is increased, the temperature of the focal spot 31 will also increase, giving rise to a more intense inverse electron beam 32.

Ordinarily the spacing between the anode 10 and cathode 11 will be such that the inverse electron beam 32 will strike the cathode head 22. In the tube as illustrated, the inverse electron beam 32 impinges upon the cathode head 22 in an inverse focal spot adjacent the bottom of the focusing cup 23, the spot being indicated in Fig. 4 at 34. It is preferable, in fact, that the inverse beam strike the cathode head so that the beam will not impinge upon the envelope 12 since electrons impinging upon the envelope 12 may cause the envelope material to deteriorate or collect upon the wall, subjecting the envelope to electrical strain under which it may fail. However, it will be apparent that similarly to the heating of the focal spot 31 on the target, the inverse electron beam 32 will cause the cathode head to heat at the inverse focal spot 34, and as the intensity of the inverse electron beam 32 increases, the heating at the inverse focal spot 34 will also increase. A limiting factor in tubes constructed in accordance with the prior art has been that the rating of the tube must be kept below the point where the cathode head melts and vaporizes by reason of the heating at the focal spot 34. The vaporized metal condenses upon the colder portions of the tube, and particularly upon the envelope, interfering with the operation of the tube. In many cases a tube may be rendered completely inoperable because of the condensed deposits.

In accordance with the present invention, the cathode head 22 is formed as a massive body of copper. Though copper has much lower melting and boiling points than any of the materials used for cathode head construction heretofore, boiling or vaporization of the copper at the

5 focal point thereon of the inverse electron flow from the anode does not occur even when the tube is operated under ratings considerably higher than permissible heretofore since the heat is dispersed from such point through the body of the head 22. As a consequence of the use of copper for constructing the head 22, a very significant increase in rating of a tube is permissible as compared with the rating at which a tube as manufactured heretofore could be operated under substantially similar conditions. In fact, as mentioned hereinbefore, with a copper cathode head the permissible tube loading is dependent upon the ability of the anode structure, rather than the cathode, to withstand injury. That is, in loading a tube 10 the possibility of injury to the copper cathode head portion can be disregarded and the maximum loading determined instead by the capacity of the anode to survive the loading since the wolfram target of the anode will become overheated before the cathode head is injured. Inasmuch as anodes have been greatly underloaded heretofore, the substitution of a copper cathode head portion makes possible an increase in permissible loading by as much as 100 percent or more. While the greater heat conductivity of copper obviously attributes to its success, other factors not at present fully understood may also contribute to the outstanding improvement in the rating of an X-ray tube resulting from its use.

Having illustrated and described a preferred embodiment of the invention, it should be apparent to those skilled in the art that the invention permits of modifications in arrangement and detail. I claim as my invention 20 all such modifications as come within the true spirit and scope of the appended claim.

I claim:

An X-ray tube for self-rectified operation comprising an 35 envelope having an anode unit and cathode unit mounted therein in facing relation, said cathode comprising a body of copper on the end thereof adjacent said anode having an electron focusing cup formed therein, and an electron generating filament mounted in said cup, said body being 40 massive whereby heat generated at the focal point thereon of the inverse electron flow from said anode unit is dispersed through said body to prevent over heating and excessive vaporization of said body at said focal point.
